Constantine P. Billings
ATTORNEY

UNITED STATES PATENT OFFICE.

LOUIS STEINBERGER AND GUY HILL, OF BROOKLYN, NEW YORK.

INSULATED SUPPORT FOR ELECTRICAL CONDUCTORS.

Application filed May 18, 1918. Serial No. 235,334.

To all whom it may concern:

- Be it known that we, LOUIS STEINBERGER and GUY HILL, citizens of the United States, and residents, respectively, of the 5 borough of Brooklyn, county of Kings, State of New York, have jointly invented certain new and useful Improvements in Insulated Supports for Electrical Conductors, of which the following is a specification.
- 10 Our invention relates particularly to insulated inductance coils for use with currents of high frequency and high potential, and thus especially adapted for use in radio apparatus.
- 15 One of the objects of our invention is to provide a mounting of insulating material for the inductance coil, said coil being molded to the insulating body in such fashion as to be exposed upon both sides thereof.
- 20 Another object is to provide an inductance coil with an internal insulating support molded to the coil throughout the central horizontal plane thereof.
- Another object is to combine a mounting 25 of insulating material with an inductance coil in such fashion as to secure the coil rigidly to the insulating material at a single molding operation, the coil being exposed upon both sides of the support of insulating material.
- 30 Another object of our invention is to provide a simple efficient inductance coil for use for high frequency, high tension currents, which is easy and inexpensive to manufacture, and which has high mechanical strength and high electrical efficiency.
- 35 Other objects will appear from the specification and claims:
- Referring to the drawings in which similar reference characters indicate like parts in the several views;
- 40 Fig. 1 is a plan view of a support of insulating material and an inductance coil secured thereto embodying our invention.
- 45 Fig. 2 is a section on line 2—2 of Fig. 1.
- Fig. 3 is a fragmentary view of a strip of an inductance coil showing the preferred construction affording means for securing the coil to the insulating material.
- 50 Our invention herein shown and described may be applied to any convenient form of support and we have shown as illustrative of the support a disc or plate S of solid insulating material.

In the embodiment of our invention the 55 spiral coil C is preferably constructed from a metal strip, the width of which is sufficient to extend out upon both sides of the central plate or support of insulating material as at a and b when the said plate or support 60 is molded to the central portion of the strip, as clearly shown in Fig. 2.

Our invention contemplates securing the plate of insulating material to the central portion of the coil, at a single molding 65 operation, holes c being provided along the central line of the strip forming the coil so that the coil C is securely anchored to the plate S of insulating material by the said material passing through the holes during 70 the process of manufacture.

As shown in Fig. 1 h are holes for securing means to hold the plate in fixed relation to the operating parts.

The said metal strip is molded to the plate 75 of insulating material at one operation and it will be seen that it is simple in construction, easy and inexpensive to manufacture, and of high electrical and mechanical efficiency.

The material used in the construction of the supporting plate may be of any suitable insulating material, but we prefer to use for that purpose the insulating material which is known in the art as "electrose." The strip 85 from which the inductance coil is formed is made of metal or any suitable kind of metallic alloy.

As changes of construction could be made within the scope of our invention, it is intended that all matter contained in the above description or shown in the accompanying drawings shall be interpreted as illustrative and not in a limiting sense.

Having now described our invention what 95 we claim as new and desire to secure by Letters Patent is:

1. In a device of the kind described, a support of insulating material, a metal coil molded at its center to the said support, the 100 edges of the said coil being exposed upon each side of the support.
2. In a device of the kind described, an integral support of insulating material molded to the central portion of an integral 105 metallic coil, the edges of the coil being exposed on each side of the support.
3. In a device of the kind described, a sup-

port of insulating material, a metal coil consisting of a strip molded to the support, the support lying in a median plane of the coil, the coil extending from the support on each side thereof.

4. In a device of the kind described, a support of insulating material, a metal coil consisting of a strip molded to the support, the support lying in a median plane of the coil, the coil extending from the support on each side thereof, means on the coil to secure the same rigidly to the support of insulating material.

5. In a device of the kind described, a sheet support of solid insulating material, a spiral inductance coil intimately secured at its center to the said sheet support, the edges of the said coil being exposed upon each side of the said solid sheet support.

6. In a device of the kind described, a support consisting of a sheet of insulating material and a metal coil consisting of a strip secured to said sheet of insulating material, said sheet lying in a plane intermediate the planes of the exposed edges of the coil.

7. In a device of the kind described, an integral support of insulating material and a metal coil consisting of a strip intimately secured to the integral support, said support

lying in a plane midway of the planes of the exposed edges of the coil.

8. In a device of the kind described, a supporting sheet of insulating material, a metal coil consisting of a strip rigidly secured to the said supporting sheet, in a plane median of the coil edges, the said coil projecting from each face of the insulating sheet.

9. A coil structure comprising a supporting web member consisting of a sheet of insulating material and a convolution of conducting material carried thereby at right angles to the plane of the web member and projecting beyond its opposed faces.

10. A coil structure comprising a supporting web member consisting of a sheet of insulating material and a convolution of conducting material molded thereto at right angles to the plane of the web member and projecting beyond its opposed faces.

In witness whereof we have hereunto set our hands at the borough of Manhattan, city and State of New York, this eighth day of May, 1918.

LOUIS STEINBERGER.
GUY HILL.

In presence of—

JOHN J. RANAGAN,
ZITA M. GRAHAM.
